LUDWIG H. WESSEL AND HOMER N. BOOKER, OF LANCASTER, OHIO, ASSIGNORS TO THE HERMANN MANUFACTURING COMPANY, OF LANCASTER, OHIO, A CORPORATION OF OHIO

MACHINE FOR REFINING PAPER AND PULP

Application filed July 5, 1928. Serial No. 290,479.

Our invention relates to machines for refining paper and pulp. It pertains, particularly, to that type of paper and pulp refining machine known as a Jordan engine and to that part of a Jordan engine that is known as a liner or shell for the so-called plug body forming a part of each engine.

Jordan engines in themselves consist of an outer shell or casing of frusto-conical form whose interior is provided with a liner or filler having a plurality of knives or cutting blades projecting inwardly from the inner surface thereof. Also, such outer shell or casing contains a rotatable plug body of frusto-conical form which has cutting blades or knives projecting outwardly, either from a liner disposed on such plug body or from the outer periphery of the plug body itself. The respective outwardly and inwardly extending knives or cutting blades are of such relative length as to coat with each other to masticate, refine or hydrate paper or pulp stock which passes therethrough from one end to the other.

In the constructions wherein the outwardly extending knives or cutting blades are disposed on a liner which is, in turn, mounted on the plug body, it has heretofore been customary to construct the liner and knives or cutting blades by casting them in a single piece. This is due to the fact that, since the knives or cutting blades on the plug body are the moving ones and masticate or break up the paper or pulp stock by passing it between

themselves and stationary knives or cutting blades, it has been believed that the mounting for the removable moving knives or cutting blades could not be sufficiently strong to withstand the strains imposed thereon by the re-

fining action since cast knives of the thin section necessary for many grades of pulp could not be made. Consequently, the usual plug liners or shells could not be used heretofore on such grades of pulp. With the

knives or cutting blades cast integrally with the liner, an entirely new liner with knives or cutting blades must be provided as replacement when the knives or cutting blades on the liner already disposed on the plug body become worn or broken to such an extent as

to no longer be useful and effective as a refining element.

If the plug body is so constructed that the outwardly projecting knives or cutting blades are mounted directly on the outer surface of the plug body, such knives or cutting blades when worn or broken are replaced by removing the plug and mounting new knives or cutting blades thereon. The length of time that is required to replace the worn out or broken knives with new knives or cutting blades is often excessive in that it requires that the refining engine be shut down while the plug body is removed, the broken or worn out knives or cutting blades taken therefrom, new knives or cutting blades individually mounted thereon and the plug body reassembled with the engine. In places where only one refining engine is used, a shut-down extending over other than a short period of time is often very expensive.

Our invention contemplates the provision of a liner for a plug body having the knives or cutting blades removably mounted thereon instead of cast integrally therewith. With such construction, when the knives or cutting blades that project outwardly from the plug body become worn or broken, the period of necessary shut-down of the engine will only extend over that time which is required to remove a plug body from the engine, remove the liner therefrom, mount a replacement liner on the plug body and reassemble the plug body with the remainder of the engine.

By providing a plug body liner with the knives or cutting blades removably mounted thereon, we have not only provided a means for shortening the time period of a necessary shut-down to replace worn out or broken outwardly projecting knives or cutting blades but we have provided a means whereby replacement knives or cutting blades may be kept in readiness for operation with a minimum of expense. This is due to the fact that the knives or cutting blades being removably mounted on a liner permit replacement liners to be kept in stock by the manufacturer with a minimum of expense. For instance, it is very apparent that plug body liners would be

much less expensive than the plug bodies themselves and that it would be prohibitive for a manufacturer to carry a number of plug bodies with knives or cutting blades mounted thereon in stock for use merely as replacements for plug bodies on which the knives or cutting blades have become worn or broken to such an extent as to impair their usefulness as a refining element of the machine.

5 19 Other advantages and objects of our invention may be seen in the following detailed description and the preferred embodiment of our invention may be seen in the accompanying drawing wherein similar characters of reference designate corresponding parts and wherein:

Figure 1 is a side view, partly in section, showing a plug liner with the cutting blades or knives removably mounted thereon.

20 20 Figure 2 is an end view, partly broken away, of the liner shown in Figure 1.

Figure 3 is a side view, partly in section, showing the liner shown in Figures 1 and 2 as being partly mounted on a conventional

25 plug body.

Figure 4 is a detail, partly in section, showing how the cutting blades or knives are secured to the plug liner.

With reference to the drawing, we have 30 shown the preferred embodiment of our invention as comprising a liner or shell 1 of frusto-conical form that is adapted to be mounted on a frusto-conical plug body 2 as shown in Figure 3.

35 35 In Figure 2 of the drawing, it will be seen that the outer surface of the frusto-conical liner or shell 1 is provided with a plurality of grooves 3 which extend longitudinally of the liner or shell and are dis-

40 40 posed on the outer surface thereof. It will further be seen by referring to Figure 1 of the drawing that a plurality of circular bands, preferably of steel and varying in diameter, are disposed along the exterior of 45 the liner or shell 1 in spaced relation to each other.

Knives or cutting blades 5 that are of substantially the same length as the liner or shell 1 and of such width as to be insertable into 50 50 the longitudinal grooves 3 are provided and these knives have mortised grooves 6 disposed along the inner edges thereof at points corresponding to the position of the respective rings or bands 4 hereinbefore described. One 55 end of each of the respective knives is bevelled as shown at 7 in Figures 1 and 3 and then extends in parallelism with the outer periphery of and toward the larger end of the shell or liner 1.

60 60 In mounting the knives or cutting blades on the liner 1, each knife or cutting blade is mounted on the liner in such manner that the bands 4 will enter the mortised grooves 6 and the inner edge of the knife will enter one 65 of the grooves 3. The knife is then driven

towards the large end of the frusto-conical shell or liner until the bands 4 enter the mortises 8 of the mortised grooves 6. A wood spacer or filler 9 is then placed adjacent the knife or cutting blade so mounted and then another knife or cutting blade mounted on the shell or liner in the same manner as hereinbefore described. The wood spacers or separators have been held in position in various ways. After all of the knives or cutting 70 blades and the respective wood spacer or filler blocks 9 have been placed on the outer surface of the shell or liner 1, in the manner shown in Figure 2, a metal band 10 is shrunk around the smaller end of the shell and the ends of the knives or cutting blades as shown in Figures 1 and 3, to prevent longitudinal movement of the knives or cutting blades.

As shown in Figure 3, the liner 1 with the knives or cutting blades 5 mounted thereon, is adapted to be mounted on a plug body 2. It will be understood that any means may be employed to secure the liner on the plug body.

Referring to the preceding description and the drawing attached hereto, it will be apparent that we have provided a device having many novel and advantageous features. For instance, we have provided a shell or liner for the plug body of a Jordan engine 95 from which the knives or cutting blades project outwardly and from which such knives or cutting blades may be removed. When the knives or cutting blades on one liner or shell become worn or broken, the liner with the knives or cutting blades thereon may be removed and another liner or shell having new knives or cutting blades thereon may be substituted in its stead.

Further, by providing a shell or liner from which the knives or cutting blades may be removed it has made it possible to replace worn or broken knives or cutting blades on the liner and has made possible the use of a liner on grades of pulp requiring thin knives.

Having thus described our invention, what we claim is:

1. In a refining engine, a plug body, a removable shell or casing to be mounted thereon, a plurality of bands carried by said shell, each of said bands having a constant diameter, a plurality of removable knives, each of said knives having an undercut groove with a surface slidably into wedging position beneath said band.

2. In a refining engine, a plug body, a removable shell or casing adapted to be mounted thereon, grooves extending longitudinally of the periphery of said shell or casing, a plurality of bands carried by said shell or casing, each band having a constant diameter, a plurality of removable knives adapted to be located in said grooves, each of said knives having an undercut mortise extending longitudinally thereof and a surface slidably into po-

sition beneath said bands so as to wedge between said bands and the bottom of said grooves.

3. In a refining engine, a plug body, a shell or casing having spaced longitudinal grooves therein adapted to be mounted on said plug body, cutting blades having morticed grooves on the under surface thereof, adapted to interfit with the longitudinal grooves on said 10 casing, spacing means adapted to be inserted between adjacent cutting blades, and means for securing said cutting blades to said shell or casing, said means embodying circular bands of constant diameter around the exterior of said shell or casing that interfit with the inner edges of the blade located below the morticed grooves in such a manner as to wedge said surfaces between said band and said groove, and a circular member adapted 15 to engage the outer edges of said cutting blade.

In testimony whereof we hereby affix our signatures.

LUDWIG H. WESSEL.
